DEBARKATION LADDER

Nathan G. Margolin and Edgar M. Anderson, Brooklyn, N. Y., assignors, by direct and mesne assignments, of one-half to Noel L. Dahlander, New Milford, Pa., and one-half to Robert J. Earl, New Canaan, Conn.

Application June 9, 1943, Serial No. 490,168

4 Claims. (Cl. 228—40)

This invention relates to ladders and more particularly to a debarkation ladder.

The principal object of this invention is to provide a debarkation ladder for use on all types of ships to permit large numbers of soldiers, sailors or marines to debark at the same time from a ship, the debarkation ladder being formed of a plurality of parallel lengths of equally spaced chains, each pair of chains having affixed thereto rungs; and spaced apart lengthwise of the ladder are booms the ends thereof extending laterally outwardly beyond the endmost chains, the booms being attached to said chains for abutting engagement with the sides of the ship and for maintaining the chains of the ladder spaced from the side of the ship so as to permit safe use of the ladder and to facilitate quick descent thereon.

Another object of the invention is to provide the upper end of each of the chains with a ring for fastening the ladder to a plurality of suitable hooks secured on the rail or deck of the ship; the lower ends of the chains being each secured to a pipe adapted to be submerged in the water and serving by its weight to hold the ladder taut.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein—

Figure 1 shows a diagrammatic elevational view of the debarkation ladder.

Figure 2 is a sectional view taken on line 2—2, Figure 1.

Figure 3 is a detail view partly in section of one end of a boom.

Figure 4 is a sectional view on line 4—4, Figure 2, showing details of rung construction.

Figure 5 is a sectional view on line 5—5, Figure 4, showing details of rung construction.

Figure 6 is a detail view showing rung connections to chain of ladder.

Figure 7 is a detail view partly in section of one end of pipe weight at bottom of ladder.

Figure 8 is an exploded view in perspective of end of rung and associated ferrule.

Referring to the drawing in detail, 10 denotes

generally the debarkation ladder which comprises, in the form shown in Figure 1, six chain elements 11, each of the same length and of a suitable size and strength. It is to be understood that the number of chains 11 utilized is a matter of choice depending on the size of debarkation ladder desired. The six chain elements 11 are retained in laterally spaced apart parallel relation by rungs 12 and booms 13, and thus define ladder sections A, B, C, D and E.

Preferably to facilitate ease of manufacture and to reduce cost to a minimum the rungs 12 are made of the same size resulting in the ladder sections being of equal width. As the rungs 12 are of the same size and as the connections thereof to the chain elements are the same a detailed description of one rung and its connections will suffice.

The rung 12 is preferably made of wood of a character suitable for the purpose intended and is shaped square in cross-section. At each end the rung 12 is provided with an annular groove 15 which is adapted to receive in friction tight engagement, a ferrule 16, the outer edge of which is to lie flush with the end of the rung. Secured to the end portions of the rung are clips, such as the eye elements 17 formed of strap iron, shaped to provide a loop such as the eye portion 18, shoulder portions 19 and arm portions 20 adapted to engage the sides 21 of the rung with the shoulder portions 19 in abutment with the end of the rung. Rivets 21 securely fasten the eye element 17 to the rung in the manner readily apparent. The eye portions 19 are of a size to receive therein a link 22 of the chain 11, and a bolt 23 extends through the walls of the eye portion 19 and through the loop formed by the link 22 for retaining each end of the rung 12 in fixed relation to an adjacent chain 11. The ferrule 16 serves as a strengthening and wear member, preventing fracture of the end of the rung and wear thereof due to movement of the chain link 22 in the eye portion 18. As will be apparent from the above, the rungs 12 are joined to the chain elements 11 by a connection of maximum strength and efficiency. The construction is such that in the event a rung is broken the same may be easily removed from the chain elements and replaced.

The rungs 12 are equally spaced lengthwise of the chain elements 11 in each ladder section, those in one ladder section being offset one link above or below those in an adjacent ladder section, as clearly shown in Figure 1.

The lowermost ends of the chain elements 11

are secured to a pipe 25 which functions by virtue of its weight to hold the chain elements 11 taut when the debarkation ladder is suspended along the side of a ship. U-bolts 26 secure the lower link of each chain element 11 to the pipe 25, the arms 27 of the U-bolts extending through openings 28 provided in the pipe, and nuts 29 on the arms 27 serve to retain the U-bolts in position.

In order to hold the debarkation ladder in spaced relation to the side 30 of the ship, there is provided a plurality of booms 13 spaced apart lengthwise of the ladder at suitable intervals. Each boom 13 is of a length slightly in excess of the width of the debarkation ladder and is preferably formed of wood, and cylindrical in shape. As the booms are each identical and are connected in the same manner to the chain elements 11, a description of one and its connections will suffice.

Provided in the boom 13 are openings 35 spaced apart a distance corresponding the spacing between the chain elements 11, and lying in the same plane. Positioned in each opening 35 is an eye-bolt 36 provided with a head flange 37 adjacent the eye 38. A washer 39 and nut 40 on the other end of the eye-bolt serves to securely attach the same to the boom, in the manner readily apparent. Secured to the eye 38 of the eye-bolt is one end of a closed link element 42, of any desired shape, the other end thereof being connected to a link of the chain element 11, as clearly shown in Figure 2. By this form of connection, the booms 13 are suspended from the chain elements 11 and at the same time serve to space the same from the side of the ship.

The upper link of each chain element 11 has affixed thereto a ring 45, which is designed for attachment to a suitable hook or stanchion 46 mounted on the railing or deck of the ship to thereby suspended the debarkation ladder therefrom, see Figure 1.

From the above description and showing in the drawing it is believed that the manner of use of the debarkation ladder embodying the features of this invention is readily apparent. The debarkation ladder 10 is of exceptional strength, is easily handled and stored, and is ready for use by simply attaching the rings 45 to the hooks 46 and dropping the ladder overboard. Preferably the length of the ladder is such that the lower end thereof will be submerged in the water, and as described above, the pipe 25 by virtue of its weight will hold the ladder taut. The five ladder sections A to E will permit men to descend the same five abreast thus providing for a quick and safe debarkation from the ship.

Having thus described the invention, what is claimed is:

1. In a debarkation ladder including at least one ladder section comprising a pair of chain elements, a plurality of rungs connecting said chain elements and uniformly spaced, each said

rung being non-circular in cross-section, an eye element including an eye portion, shoulder portions and opposed arm portions fitted to the end of each rung with the terminal end of the rung abutting said shoulder portions, means fastening said arm portions to the sides of said rung, each eye portion encircling a link of a chain element, bolt means extending through each eye portion and associated link for holding the same in assembled relation, said rung having an annular recess formed in each terminal end thereof, and a reinforcing and wear preventing ferrule seated in each annular recess.

2. In a debarkation ladder including at least one ladder section comprising a pair of chain elements, a plurality of rungs connecting said chain elements and uniformly spaced, an eye element including an eye portion, shoulder portions and opposed arm portions fitted to the end of each rung with the terminal end of the rung abutting said shoulder portions, means fastening said arm portions to the sides of said rung, each eye portion encircling a link of a chain element, and bolt means extending through each eye portion and associated link for holding the same in assembled relation.

3. In a multiple debarkation ladder of the class having a plurality of longitudinally extending chain stiles and rungs having their ends connected to said stiles wherein the rungs of adjacent rows are staggered relative to one another and connected to different links in any one chain to enable movement between the different links to be effected, a clip at each end of each rung, comprising an eye portion, shoulder portions and opposed arm portions fitted to the end of each rung abutting said shoulder portions, means fastening said arm portions to the sides of said rung, each eye portion encircling a link of a chain element, and bolt means extending through each eye portion and associated link for holding the same in assembled relation.

4. In a multiple debarkation ladder of the class having a plurality of longitudinally extending chain stiles, each composed of looped links, and rungs having their ends connected to said stiles wherein the rungs are movable relative to one another and to the stiles and the rungs of adjacent rows are staggered relative to one another and connected to different links in any one chain to enable movement between the different links to be effected, an eye element at the end of each rung including an eye portion, shoulder portions, and opposed arm portions fitted to the end of each rung, said end abutting said shoulder portions, means fastening said arm portions to the sides of said rung, each eye portion encircling a link of a chain element, and bolt means extending through each eye portion and associated link for holding the same in assembled relation.
